UNITED STATES PATENT OFFICE.

L. J. Atwood.

Lamp Burner

Specification forming part of Letters Patent No. 36,493, dated September 16, 1862.

To all whom it may concern:

Be it known that I, LEWIS J. ATWOOD, of Waterbury, in the county of New Haven and State of Connecticut, have invented, made, and applied to use a certain new and useful Improvement in Lamps; and I do hereby declare the following to be a full, clear, and exact description of my said invention, reference being had to the annexed drawings, making part of this specification, wherein—

Figure 1 is a vertical section of my improvement in lamps. Fig. 2 is an inverted plan. Fig. 3 is an inverted plan with the wick-tube removed. Fig. 4 is a side view of the spring that acts on a lever to hold the glass chimney. Fig. 5 is a plan of the ratchet-cap, and Fig. 6 is a section of the wick-tube and ratchet-cap.

Similar marks of reference denote the same parts.

My invention relates to the well-known class of lamps in which a deflector is applied above the wick-tube, rising within a glass chimney, and the lamp is adapted especially to the burning of coal-oils.

My invention consists in forming the lower part of the wick-tube flaring or bell-muzzling, in order that the wick may be entered more easily and not be liable to catch. I also make use of this flaring wick-tube in combination with projections about the middle of the wick-tube, to hold the wick-tube, ratchet-cap, and exterior shell of the burner together. I also attach the lower end of the spring that is employed in holding on the glass chimney directly to the side of the wick-tube without the employment of solder, and I guide and steady the said spring by the cap that contains the ratchet for raising and lowering the wick.

In the drawings, *a* is the screw-cap or exterior shell, setting upon any ordinary reservoir or receptacle for the material to be consumed. This shell rises in the form of an inverted perforated cone to the ring *b* and receives the base of the glass chimney, as seen at *c*.

d is the ordinary deflector rising above the wick-tube *e*, and *f* is the ratchet for raising and lowering the wick. *i* is the ratchet-cap setting within the shell *a*.

In order to secure the ratchet-cap *i*, shell *a*, and wick-tube *e* together, I provide projections *6 6* on the edges of the wick-tube, near

the middle of the same, above the ratchet-cap, and I spread out the lower end of the wick-tube, as at 5, in a flaring or bell-mouthed shape by means of a tapering punch, which operation holds the ratchet-cap, shell, and wick-tube firmly together without solder, and at the same time makes the end of said wick-tube much better for entering the wick, because the edges thereof will not catch in the said wick.

g is a bent lever passing through the cap at the point *l*, which forms a fulcrum for said lever to move on, and *h* is a spring acting upon the inner end of this lever to cause the angle bent in said lever to hold the glass chimney *c* in place, as seen in Fig. 1, and the amount of motion allowed to this lever is limited by small projections *2 2* from the lugs on the ring *b*. In order to secure this spring *h* in place, I make two notches therein, as at *3 3*, Fig. 4, and at the side of the opening in the shell *a*, through which the wick-tube *e* passes, I form a notch, as at *4*, sufficient to receive the shank of the spring *h*, the edges of the shell *a* entering the notches *3 3*. The wick-tube is to be slid through the opening in *a* after this spring is in place; or the side of the wick-tube may be slightly bent in sufficient to allow the spring to be introduced, when, by forcing into this lower end of the wick-tube the tapering punch, as aforesaid, the tube will be spread or made bell-mouthed, as at 5, effectually securing the spring in place against the side of the wick-tube. It will be evident that this spring, setting against the side of the wick-tube, gives facility for securing the same without the use of solder, and for this purpose rivets or ears might be employed; but I prefer the means shown. In order to steady the said spring *h* and prevent any sidewise movement, I provide a notch in the ratchet-cap, as at *7*, Fig. 5, contiguous to the wick-tube, and said spring in passing through the said notch is guided and retained in place at the same time that it is not prevented from springing as the lever *g* is pressed upon.

My burner is simple, durable, easily constructed, and is not injured in any of its parts by the heat to which it is exposed.

What I claim, and desire to secure by Letters Patent, is—

1. Forming the lower end of the wick-tube

flaring or bell-mouthed, in the manner and for the purposes specified.

2. The ratchet-cap, wick-tube, and exterior shell of the burner, in combination with the projections 6 6, near the middle of the wick-tube and the bell-mouth 5 at the lower end of said wick-tube, whereby the parts are held together, as set forth.

3. Fastening the lower end of the spring *h* against the side of the wick-tube without solder, in substantially the manner specified.

4. The ratchet-cap *i*, with the notch *j*, in combination with the wick-tube *e* and spring *h*, for holding the said spring from moving sidewise, substantially as set forth.

In witness whereof I have hereunto set my signature this 7th day of July, 1862.

LEWIS J. ATWOOD.
